UNITED STATES PATENT OFFICE

JOHN F. MOEN, OF NEW YORK, N. Y.

EXPLOSIVE-ENGINE.

1,149,670.

Specification of Letters Patent. Patented Aug. 10, 1915.

Application filed March 27, 1914. Serial No. 827,718.

To all whom it may concern:

Be it known that I, JOHN F. MOEN, a citizen of the United States, residing at New York city, borough of Brooklyn, county of Kings, and State of New York, have invented new and useful Improvements in Explosive-Engines, of which the following is a specification.

This invention relates to an explosive engine of novel construction and more particularly to novel and simple means for controlling the influx of the explosive mixture into each cylinder and for effectively expelling the exploded gases therefrom. The invention also includes other novel features of construction as more fully pointed out in the appended specification and claims.

In the accompanying drawing: Figure 1 is a side view of an engine embodying my invention; Fig. 2 a longitudinal section through one of the cylinders and adjoining parts; Fig. 3 a cross section on line 3-3, Fig. 2; Fig. 4 a similar section on line 4-4, Fig. 2; Fig. 5 an outer view of one of the valves, its surface being laid out into a plane, and Fig. 6 a similar outer view laid out in a plane, of the inner surface of one of the cylinders.

Each cylinder 10 of my improved explosive engine 11 is provided with a lower bore 12 adapted to snugly embrace the piston 13 and with an upper bore or recess 14 of a diameter that exceeds that of bore 12. Within bore 14 is rotatably mounted an inverted cup-shaped valve 15 comprising a cylinder 16 and an integral upper wall or disk 17. The inner bore 18 of valve 15 equals in diameter the bore 12 of cylinder 10 so as to be also adapted to snugly embrace piston 13. From wall 17, there extends upwardly a stem 19 passing through a corresponding bore of a cover 20 removably secured to the top of cylinder 10 in suitable manner. Between wall 17 and cover 20 is interposed a plurality of antifriction balls 21 guided by rings 22 and taking up the upward thrust of valve 15 during compression, explosion and exhaust while reducing the friction of the valve during its rotation to a minimum.

Upon each stem 19 is firmly mounted a worm wheel 23 and a fly wheel 24, the wheel 23 engaging a worm 25. The worms 25 of the several stems 19 are mounted on a common shaft 26 which is provided at one end with a sprocket wheel 27. The latter is, by chain 28, connected to a similar wheel 29 of

crank shaft 30 to which motion is transmitted from each piston 13 through a pitman 31. The ratio between the parts 29, 27, 25, 23 should be such that each valve 15 makes one complete revolution while shaft 30 performs two revolutions, the engine being shown to be of the four cycle type. Shaft 30 carries the usual fly wheel 32, while the individual fly wheels 24 of valves 15 tend to maintain a uniform non-vibratory rotation thereof so as to render the movement of said valves independent of any jerks of the chain in case the latter has become slightly slackened owing to prolonged use or inaccurate adjustment. The spokes 24^a of each fly wheel 24 are set at an incline so as to constitute a fan that produces a down draft on the top of cylinder 10 and thus assists in the cooling of the engine.

Cylinder 10 is provided near its top with an inlet port 33 and a main exhaust port 34, the port 34 being located higher than port 33 so as to be out of horizontal alignment with the latter as indicated by the upper dot and dash line in Fig. 6. Ports 33 and 34 are arranged diametrically opposite each other and are each of a length to correspond approximately to one eighth of the inner circumference of the upper bore of cylinder 10. In addition to port 34, cylinder 10 is provided with an inclined or oblique supplementary port 35, the upper end of which is located slightly below the lower edge of port 34 (see lower dot and dash line, Fig. 6) while the lower end of port 35 lies slightly above the top of piston 13 when the latter occupies its lowermost position (Fig. 2). In vertical direction, the right and left hand terminals of port 35 coincide with those of port 34, port 35 thus occupying in circumferential direction also about one eighth of the inner circumference of the upper bore of cylinder 10. Inlet port 33 communicates with the inlet manifold 36, while both of the exhaust ports 34, 35 open into a common exhaust chamber 37 of a height that equals substantially the aggregate height of port 34, 35 plus the height of the web 38 formed between said ports, chamber 37 being connected to the usual exhaust manifold (not shown) through branch 39. The cylinder 10 is surrounded by a cooling jacket 40 extending above and below exhaust chamber 37 so as to permit a free circulation of the cooling medium.

The cylindrical portion 16 of valve 15 is

provided with an inlet duct 41 adapted to become alined with inlet port 33 and with a main exhaust duct 42 and an inclined or oblique supplementary exhaust duct 43, the 5 inclination of duct 43 being opposite to that of port 35 as clearly indicated in Figs. 5 and 6. Duct 42 is located higher than duct 41 so as to be out of horizontal alinement therewith, while the upper end of duct 43 10 is located slightly lower than duct 41, as indicated by dot and dash lines in Fig. 5. In circumferential direction, all of the ducts 41, 42, 43 occupy about one eighth of the outer circumference of cylinder 16, duct 41 15 being spaced from the vertically alined ducts 42, 43 by a solid cylinder portion of also about one eighth of such circumference (Fig. 5).

As valve 15 receives continuous rotation 20 in the direction of the arrow 44 in the manner described, a properly timed alternate intake of the explosive charge and exhaust of the exploded gases takes place. In the position of valve 15 shown in Figs. 2, 3, 4, 25 5, and 6, the piston 13 has just completed its power stroke and exhaust is about to commence. During the subsequent registering of ducts 42, 43 with ports 34, 35 respectively, the main exhaust port 34 will be gradually 30 opened and closed, while the lower portion of the inclined duct 43 will first overlap the corresponding lower portion of the oppositely inclined port 35, whereupon the overlapping point of said duct and port will 35 gradually rise to form a movable exhaust opening until port 35 is closed at its top which closure coincides timely with the arrival of piston 13 at its topmost position. As the period of time elapsing between the 40 start and finish of the gradual rising of the movable exhaust opening formed by the duct 43 and port 35, corresponds to two eighths or one quarter of a complete revolution of valve 15, which time is also consumed 45 by the exhaust stroke of piston 13 and as furthermore the lower ends of the ports 43, 35 are made to overlap prior to the arrival of the ascending piston at said overlapping point, it is obvious that the ascending piston 13 will slightly lag behind the likewise 50 ascending movable exhaust opening, during which time the main exhaust port 34 is also open. In this way, the exploded mixture is most effectively expelled from the cylinder 55 prior to the admission of the fresh charge. As soon as the exhaust ports 34, 35 have been closed, inlet duct 41 will register with port 33, to admit a fresh explosive charge into cylinder 10 while piston 13 descends. 60 During the subsequent upstroke of the piston, all ports are closed to permit a compression of the charge, while at the end of the compression stroke of the piston, ignition takes place. In order to reduce the 65 number of ducts provided in valve 15 to

minimum, the spark plug 45 is fitted into the upper part of cylinder 10 at that point which happens to be uncovered by the inlet duct 41 at the precise moment when ignition should take place, the actual location of 70 plug 45 being clearly indicated in Figs. 3 and 6.

It is to be understood that the particular construction of the engine as shown and described, constitutes but one embodiment of 75 my invention, and that various changes more particularly relating to the shape and position of the several valve ports may be made without departing from the spirit of my invention.

It will be seen that a machine of the general construction described, may be easily manufactured, comprises but a minimum 80 number of operative parts which are readily accessible, and is reliable and effective in 85 operation.

I claim:

1. An explosive engine comprising a cylinder having an inlet port and an inclined 90 exhaust port, a cylindrical valve rotatably mounted within the cylinder and having an inlet duct which is adapted to register with the inlet port and an exhaust duct which is inclined in a direction opposite to that of the exhaust port of the cylinder and is 95 adapted to register therewith, and a piston slidably engaging the valve.

2. An explosive engine comprising a cylinder having an inlet port and an inclined 100 exhaust port, a hollow valve rotatably mounted within the cylinder and having an inlet duct and an exhaust duct which is oppositely inclined relatively to the exhaust port of the cylinder, a piston adapted to slidably engage the hollow valve, a crank 105 shaft adapted to be actuated by the piston, and means for operatively connecting the crank shaft and valve.

3. An explosive engine comprising a cylinder having an inlet port, a main exhaust 110 port and an inclined supplementary exhaust port, a hollow valve rotatably mounted within the cylinder and having an inlet duct, a main exhaust duct and a supplementary exhaust duct inclined oppositely 115 to the exhaust port of the cylinder, a piston slidably engaging the hollow valve, a crank shaft adapted to be actuated by the piston, and means for operatively connecting the crank shaft to the valve.

4. An explosive engine comprising a cylinder having an inlet port, a main exhaust port and an inclined supplementary exhaust port, a hollow valve rotatably mounted within the cylinder and having an inlet 125 duct, a main exhaust duct and a supplementary exhaust duct inclined oppositely to the exhaust port of the cylinder, a spark plug carried by the cylinder and adapted to be uncovered by the inlet duct of the valve, a 130

piston slidably engaging the valve, a crank shaft adapted to be actuated by the piston, and means for operatively connecting the crank shaft to the valve.

- piston slidably engaging the valve, a crank shaft adapted to be actuated by the piston, and means for operatively connecting the crank shaft to the valve.

5 5. An explosive engine comprising a cylinder having an inclined exhaust port, a valve rotatably mounted within said cylinder and having an exhaust duct which is inclined oppositely to the exhaust port of the cylinder, said port and duct being adapted to jointly form a movable exhaust opening, and a piston slidably engaging the valve and adapted to lag behind said movable opening during its exhaust stroke.

10 15. 6. An explosive engine comprising a recessed cylinder having an inlet port, a main exhaust port and an inclined supplementary exhaust port, a valve rotatably mounted within the cylinder-recess and having an inlet duct, a main exhaust duct and a supplementary exhaust duct inclined oppositely to the supplementary exhaust port of the cylinder, said supplementary port and duct being adapted to jointly form a movable exhaust opening, an exhaust chamber with which the exhaust ducts of the valve are adapted to communicate, a cooling jacket surrounding the cylinder and extending above and below the exhaust chamber, a piston slidably engaging the valve and adapted to lag behind the movable exhaust opening during its exhaust stroke, and means for operatively connecting the piston and valve.

20 25. 7. An explosive engine comprising a cylinder having an inclined exhaust port, a valve rotatably mounted within said cylinder and having an exhaust duct which is inclined oppositely to the exhaust port of the cylinder, said port and duct being adapted to jointly form a movable exhaust opening, and a piston slidably engaging the valve and adapted to lag behind the movable opening during its exhaust stroke, and means for operatively connecting the piston and valve.

25 30. 8. An explosive engine comprising a recessed cylinder having an inlet port, a main exhaust port, an inclined supplementary exhaust port, a valve rotatably mounted within the cylinder-recess and having an inlet duct, a main exhaust duct and a supplementary exhaust duct inclined oppositely to the supplementary exhaust port of the cylinder, said supplementary port and duct being adapted to jointly form a movable exhaust opening, an exhaust chamber with which the exhaust ducts of the valve are adapted to communicate, a cooling jacket surrounding the cylinder and extending above and below the exhaust chamber, a piston slidably engaging the valve and adapted to lag behind the movable exhaust opening during its exhaust stroke, and means for operatively connecting the piston and valve.

inclined oppositely to the exhaust port of the cylinder, said port and duct being adapted to jointly form a movable exhaust opening, and a piston slidably engaging the valve and adapted to lag behind the movable opening during its exhaust stroke, and means for operatively connecting the piston and valve. 35 40

8. An explosive engine comprising a recessed cylinder having an inlet port, a main exhaust port, an inclined supplementary exhaust port, a valve rotatably mounted within the cylinder-recess and having an inlet duct, a main exhaust duct and a supplementary exhaust duct inclined oppositely to the supplementary exhaust port of the cylinder, said supplementary port and duct being adapted to jointly form a movable exhaust opening, an exhaust chamber with which the exhaust ducts of the valve are adapted to communicate, a cooling jacket surrounding the cylinder and extending above and below the exhaust chamber, a piston slidably engaging the valve and adapted to lag behind the movable exhaust opening during its exhaust stroke, and means for operatively connecting the piston and valve.
